ASSIGNORS, BY MESNE ASSIGNMENTS, TO SIMMONS COMPANY, OF NEW YORK, N. Y.,
A CORPORATION OF DELAWARE

DAY-BED OR BOX-LOUNGE CONSTRUCTION

Application filed November 2, 1927. Serial No. 230,665.

This invention relates to improvements in beds, day beds, couches, lounges, chairs and the like, and the main object is to provide a mode of construction by which the side rails 5 of the structure are concealed from view without the use of a valance, spread or other means additional to the box or spring.

Considering, for purposes of explanation and comparison, a day bed as ordinarily constructed and especially a metal frame day bed, it is observed that the side rails which connect the ends are L-shaped in cross section and usually arranged with one flange horizontal and one flange vertical and depending from the outer edge of the horizontal flange. Sometimes the arrangement is reversed so that the vertical flange rises from the outer edge of the horizontal flange. The box or spring of the bed rests upon 20 the horizontal flange and with either of the side rail arrangements just described the whole depth of the vertical flange is visible.

According to the present invention, the side rails are of the usual type but are arranged with the vertical flange rising from the inner edge of the horizontal flange and the box or spring is provided with depending side flanges, which lie outside the vertical flanges of the side rails and rest upon 30 the horizontal flanges thereof. In this way only the thickness of the horizontal flange can be seen and, by making the box flange project slightly beyond the outer edge of the rail flange, the rail flange is invisible to 35 a person standing or sitting near the bed.

In the drawings which illustrate one embodiment of the invention but to the details of which the invention is not confined:—

Fig. 1 is a perspective view of a day bed, 40 constructed according to this invention, as ordinarily viewed, and illustrates the invisibility of the side rails.

Fig. 2 is a fragmentary cross-sectional view on the line 2—2 of Figure 1.

Fig. 3 is a plan view of the junction of the side rail and end post.

Referring more particularly to the drawings, 11 designates the ends of a day bed having corner posts 12, the side faces and inner 50 faces of which are respectively designated

13 and 14. Brackets 15 of any suitable type are rigidly secured to the inner faces 14 of the posts for support of the side rails 16, only one of which is shown, but it will be understood that there is one rail at each side 55 of the structure as usual. The side rails, which extend as usual between corresponding posts of the two ends 11, are preferably of L-shape in cross-section, as shown, and are each disposed with one flange 17 horizontal 60 and the other flange 18 vertical and rising from the inner edge of the horizontal flange, that is, the edge remote from the side faces 13 of the posts between which the rail extends. 65

The exact form of bracket 15 used is immaterial except that it must be such as will permit positioning of the side rails in the manner described and entirely inside the plane containing the side faces of the end 70 posts concerned. The form of bracket illustrated is L-shaped in plan with one flange 19 bolted or otherwise secured against the inner face 14 of the post and with the other flange 20 projecting near the edge of the 75 post remote from the side face 13. This flange 20 is slotted, as at 21, to receive a headed stud 22 rigidly secured to the vertical flange 18 of the side rail by a nut 23 or by riveting. The slot 21 and stud 22 are so 80 positioned in the members carrying them that on assembly the end of the rail jams against the flange 19 of the bracket to make a rigid connection between the rail and post. 85

The storage box or box spring, designated 24, as a whole by the numeral 24, may be of any suitable construction and includes framework 25 which is provided at each side with a depending flange 26 adapted to rest upon the horizontal flange 17 of the adjacent side 90 rail and to have sufficient clearance from the vertical flange 18 to accommodate the nuts 23 or other projections from the rail flange, if any. The depth of these flanges is preferably such as to support the frame above 95 the vertical rail flanges 18. The width of the box or spring frame is such that the sides thereof project slightly beyond the outer edges of the horizontal rail flanges. The covering of the box or spring, designated 27, 100

preferably covers the outer sides of the frame and flanges 26 and is tacked to the lower edges of the flanges.

As will be readily seen from the drawings, the relation of the rails to the posts and box or spring enables the box or spring to be provided with the depending flanges 26 which entirely conceal the vertical flanges of the rails and which project sufficiently beyond the outer edges of the horizontal flanges to effectively conceal them also. It will also be appreciated that this is accomplished without projection of the box or spring frame beyond the planes containing the side faces 13 of the posts. Such projection is to be avoided as it gives an unsightly appearance to the structure and exposes the covering at the corners and vertical edges of the box or spring to excessive wear and is furthermore liable to cause injury to a person coming in contact with the exposed corners. These results can not be obtained with side rails disposed in the usual manner.

While the invention relates particularly to structures including side rails L-shaped in cross-section, such as are now in general use, it also embraces broadly the use of a box or spring or of depending flanges on the box or spring to conceal side rails of any type. Furthermore, while the invention is directed particularly to day beds, it may be applied also to beds with box springs and to couches, lounges, chairs and the like.

Having thus described our invention, what we claim is:

1. In metal frame beds, day beds and the like, the combination with ends and a box frame, of side rails connecting the ends each of said side rails being formed with a horizontal flange and a vertical flange rising from the inner edge of the horizontal flange, said box frame including side members lying outside the vertical rail flanges supporting the box frame on the horizontal rail flanges and concealing both the vertical and horizontal flanges of the rails.
2. In metal frame beds, day beds and the like, the combination with ends of rails connecting the ends, each of said rails including a horizontal flange and a vertical flange rising from the inner edge of the horizontal flange, and a box spring frame including at each side a member resting upon the horizontal rail flange and projecting outwardly therebeyond and both supporting the frame and concealing the rail.

In witness whereof, we have hereunto set our hands.

RICHARD BRADSHAW.
REGINALD FERGUSON.
